FLUID CONTROL DEVICE

Frederick W. Taylor, Fairfax, Va., assignor to
The Trane Company, La Crosse, Wis.
Filed Feb. 6, 1963, Ser. No. 256,559
5 Claims. (Cl. 98—39)

This invention relates generally to fluid controlling devices. More particularly this invention relates to air damper means for ventilating equipment and the like wherein the damper position is varied in response to wind or draft pressures.

A first object of my invention is to provide a damper of the blow-shut type.

Another object of the invention is to provide a blow-shut damper with a bypass passage.

A further object of my invention is to provide a blow-shut damper including a bypass passage with a second damper for selectively closing said bypass passage as well as the blow-shut damper.

Still another object of my invention is to provide a damper device having at least two damper vanes wherein the first is permitted complete freedom of movement when the second is in the open position and the second operates to close the first when the second vane is moved to its closed position.

Another object of the invention is to provide a damper of the aforementioned type wherein the second damper is moved to its open position in response to the energization of a fan motor for moving air through said damper device.

And still a further object of my damper device is to provide a damper utilizing at least two damper vanes wherein one damper vane upon closing engages the other to move the same to a closed position and wherein at least one of said damper vanes is provided with resilient sealing means which, in addition to providing an air seal, functions to compensate for manufacturing variations in each of the two interacting dampers.

Other objects will become apparent as this specification proceeds to describe the invention with reference to the drawings, in which:

FIGURE 1 is a schematic view of the invention as applied to a conventional wall air conditioner or ventilator showing the damper portion in the open position;

FIGURE 2 is a vertical section taken on line 2—2 of FIGURE 1; and

FIGURE 3 is an enlarged vertical section of the damper portion of FIGURE 1 taken just inside the damper casing illustrating the blow-shut position in full line and the completely closed position in dot-dash line.

Looking now to FIGURE 1, a wall air conditioner or ventilating unit 2 is adapted for receiving room air 4, and fresh outside air at 6 through a damper device 8. The air is drawn through filter 10 to fan inlet 12 of a centrifugal fan 14 and moved through heat exchange coil 16 and exhaust louvers 18 in the unit housing 20 and hence to the conditioned room space. The fan rotor (not shown) is driven by electric motor 22 when switch 24 is closed to complete the fan motor power circuit 26 with a power source 28. Switch 24 may be thermostatically or otherwise controlled as desired.

Now referring to FIGURES 2 and 3 it will be seen that the damper device 8 is comprised of a sheet metal casing 32 including a pair of spaced parallel vertical side members 34, top member 36 and bottom member 38 extending between said side members, thus forming the sides circumscribing a generally horizontal air passageway through casing 32. Damper casing outer end wall 40 is provided with an inlet aperture 42 communicating with said passageway. Damper casing inner end wall 44 is provided

2

with an outlet aperture 46 for discharging air in said passageway to the air conditioner proper. Casing 32 also includes a partition member 48 projecting upward partially into the air passageway from casing bottom member 38 and extending between side members 34 in parallel relation to end walls 40 and 44. A baffle member 50 projects inwardly from outer end wall 40 downwardly from a point above inlet aperture 42. A resilient bumper 52 is mounted on the terminal portion of baffle member 50, the function of which is yet to be described.

The first damper assembly 30 disposed within said passageway carries a main damper vane 56 having ears 58 (FIGURE 2) extending laterally into generally triangular apertures 60 in side walls 34. The ears are free to pivot as a knife edge at one corner of triangular apertures 60. It will be seen that the pivotal axis of said first damper assembly bisects the damper passageway into a main air flow passage as illustrated by the flow vectors in FIGURE 1 and a bypass air flow passage as illustrated by the flow vectors of FIGURE 3. Main damper vane 56 is generally L-shaped in cross section having a long leg portion 62 and a short leg portion 64. The lower margin of the long leg portion may be bent as at 65 to give the vane additional strength and provide it with a suitable angular approach to resilient sealing member 66 mounted on partition member 48. Attached to long leg portion 62 are brackets 68 for supporting a counterbalance weight 70 which tends to pivotally bias first damper assembly 30 to the fully open position (as shown in FIGURE 1) abutting resilient bumper 52. The action of the wind or differential pressure across the damper passageway between end walls 40 and 44 tends to pivotally bias the first damper assembly to a closed position as shown in FIGURE 3. It will be noted that when the first damper assembly is in this closed position, that baffle 50 is disposed adjacent the crook on the concave side of the L-shaped main damper vane. This arrangement has the effect of permitting the short leg portion 64 to deflect air in a reverse path before entering the bypass passage.

Disposed above said first damper assembly 30 and also within said fluid passageway is a second damper assembly 72 for closing the bypass passage. The second damper assembly is comprised of a bypass damper vane 74 mounted for pivotal movement with support bar 78 journaled in side members 34. Rotation of the second damper assembly 72 in the counterclockwise direction (FIGURE 3) toward the closed position as shown in dot-dash line causes vane 74 to engage an engagement flange 80 on the short leg portion 64 of main damper vane 56. Further rotation of the second damper to its closed position effects the closure of the first damper assembly 56, thus completely closing the entire damper device. Damper vane 74 may have a lip 82 at the outward edge thereof for greater strength and sealing ability.

It should be noted that single resilient sealing member 66 will compensate for dimensional manufacturing variations in both of the damper vanes.

The second damper assembly is selectively actuated to its respective positions by a two position motor 84 via motor crank 86, connecting link 88 and damper support bar crank 90. The two position motor 84 may be connected to the fan motor power circuit 26 in parallel with fan motor 22 as by leads 92 (FIGURE 1). Energization of fan motor 22 also causes motor 84 to move second damper assembly 72 to the open position, thus, permitting first damper assembly 30 to swing to the open position under the bias of the counterbalance weight 70. De-energization of the fan motor 22, as by the opening of switch 24, causes motor 84 to move the second damper assembly to the closed position, thus, closing the first damper assembly.

It will thus be seen that my invention provides a novel and improved damper device adaptable for use with air conditioning and ventilating equipment to protect such equipment with a complete fresh air shut off when not in operation, and further provides protection against high wind drafts without the danger of complete fresh air shutdown while such equipment is in operation.

Although I have described in detail the preferred embodiment of my invention, I contemplate that many changes may be made without departing from the scope or spirit of the invention and I desire to be limited only by the claims.

I claim:

1. A fluid flow control device comprising the combination of: a first fluid passage; a second fluid passage; a fluid passageway in fluid communication with said first and second fluid passages; a first damper means for adjustably restricting and closing said first fluid passage; a second damper means for closing said second fluid passage; means for biasing said first damper means toward an open position; means for biasing said first damper means toward a closed position in response to a fluid pressure differential across said first fluid passage between a zone upstream and a zone downstream of said first damper means; means for selectively actuating said second damper means to a closed position; means for closing said first damper means in response to the closure of said second damper means when said first mentioned means for biasing said first damper means dominates said second mentioned means for biasing said first damper means; and means providing relative movement of said several damper means when said second damper means is in a substantially open position.

2. A ventilating device for supplying outside air to an enclosure comprising: a fan for moving outside air to said enclosure, an electric motor for driving said fan; means for energizing said electric motor; an air passageway for providing fluid communication between the inlet of said fan and an outside source of air; means bisecting said air passageway into a first and second air passage; a first damper means for adjustably restricting and closing said first air passage; a second damper means for closing said second air passage; means for biasing said first damper means toward an open position; means for biasing said first damper means toward a closed position in response to a fluid pressure differential across said first air passage; means for actuating said second damper means to the open position when said electric motor is energized and to the closed position when said motor is not energized; means for closing said first damper means in response to the closure of said second damper means; and means for permitting relative movement of said several damper means when said second damper means is in a substantially open position.

3. A fluid flow control device comprising: a casing defining a fluid passageway therethrough; said casing including first and second side members in spaced relationship defining first and second sides of said fluid passageway, first means extending between said side members forming a third side of said passageway, and a second means remote from said first means extending between said side members forming a fourth side of said passageway; a first damper assembly having a damper vane extending between said first and second side members and mounted for pivotal movement about an axis extending between said first and second side members bisecting said fluid passageway into a main fluid passage and a bypass fluid passage, said damper vane arranged to close said main fluid passage in response to a sufficient pressure differential across said fluid passageway between a zone upstream and a zone downstream of said damper vane; a second damper assembly having a damper vane extending between said side members mounted for pivotal move-

ment about an axis extending between said side members adjacent said second means; said second damper assembly arranged to close said bypass fluid passage and simultaneously engage a portion of said first mentioned damper assembly for moving said first mentioned damper vane to a position closing said main fluid passage thereby substantially closing said fluid passageway; means for permitting relative movement between said damper vanes when said second mentioned damper vane is in a substantially open position; and means other than the fluid pressure differential across said passageway for actuating said second mentioned damper vane to its closed position.

4. A fluid flow control device comprising: a casing defining a fluid passageway therethrough; said casing including first and second side members in spaced relationship defining first and second sides of said fluid passageway; first means extending between said members forming a third side of said passageway; and a second means remote from said first means extending between said side members forming a fourth side of said passageway; a first damper assembly having a main damper vane extending between said first and second side members and mounted for pivotal movement about an axis extending between said side members bisecting said fluid passageway into a main fluid passage and a bypass fluid passage; said main damper vane being generally L-shaped in cross section and when disposed in the closed position, the longer leg thereof extending across said main fluid passage in sealing engagement with said first means and the shorter leg thereof protruding partially into said bypass passage for deflecting bypass fluid into an extended path; said shorter leg further including an engagement flange at the end remote from said longer leg; a second damper assembly having a bypass damper vane extending between said first and second side members; said bypass damper vane being pivotally mounted about an axis adjacent said second means for swinging movement in said bypass passage and engagement with said engagement flange of said main damper vane; said bypass damper vane when pivoted to its open position being in nonengaging relation with said main damper vane irrespective of its position; and a baffle means mounted adjacent the crook on the concave side of said L-shaped main damper vane for directing bypass fluid against the short leg of said main damper.

5. A fluid flow control device comprising the combination of means forming a fluid passageway; a first damper assembly having a first damper vane in said passageway mounted for pivotal movement about an axis bisecting said fluid passageway into a main fluid passage and a bypass fluid passage; means responsive to the pressure differential between a zone upstream and a zone downstream of said first damper vane for adjustably positioning said first damper vane about said axis; a second damper assembly having a second damper vane in said bypass passage mounted for pivotal movement about an axis spaced from and extending generally parallel to said first mentioned axis; means for actuating said second damper vane to a closed position; means responsive to the actuation of said last mentioned means for moving said first damper vane to a closed position thereby substantially closing said fluid passageway; and means providing relative movement between said damper vanes when said second damper vane is in a substantially open position.
